TRAY FOR HOLDING MULTIPLE CARTONS
Warren H. Bates, 7224 Burns, Fort Worth, Tex. 76118
Continuation-in-part of application Ser. No. 464,720,
June 17, 1965. This application Sept. 7, 1967, Ser.
No. 666,121

1 Claim. (Cl. 229—31)

ABSTRACT OF THE DISCLOSURE

A tray for holding multiple rectangular cartons, cans or bottles, and comprised of a single rectangular blank of fiberboard or the like having score lines parallel with the sides thereof, defining the side panels of the tray, a transverse cut in said blank parallel with each end thereof and extending into the side panels, thence toward the end of the trays and then at an angle to the score lines. The primary feature of the invention has to do with eliminating bellows folds at the corners of the tray.

This invention has reference to a tray for holding multiple units such as cartons, cans or bottles. The present application is a continuation in part of my copending application Ser. No. 464,720, filed June 17, 1965, now United States Patent No. 3,347,447, which issued Oct. 17, 1967.

While the invention of my copending application is capable of serving its intended purpose, the present construction eliminates the bellows fold, thereby simplifying the assembly operations. In the case of the first construction, Patent No. 3,347,447, it was necessary to have a special head in an automatic box making machine wherein the end and side panels had to be folded at the same time. To those versed in the art it is apparent that the elimination of the bellows permits the use of simplified equipment, thus effecting a substantial saving to the tray manufacturer. Like the first invention, the present construction effects a saving of material in that the blank is only slightly longer than the resulting tray.

An object of the invention is to provide a tray of fiber paper or other bendable sheet material wherein transverse cuts become the end panels and wherein the side and end panels may be folded separately, thus permitting the use of simplified equipment for manufacturing the trays.

A particular object is to eliminate bellows folds in trays whereby conventional box making machines may be used when making trays according to the invention.

Another object, in addition to the foregoing, is to provide a tray which is only slightly less in length than the blank from which it is made, thereby effecting a saving of material.

These and other objects of the invention will become apparent from the following description and the accompanying drawing, in which:

FIGURE 1 is a perspective view of a blank for making a tray according to the invention.

FIGURE 2 is a broken perspective view similar to FIGURE 1, but showing the first folding operation.

FIGURE 3 is a broken perspective of a corner of the tray in a partly assembled position, and

FIGURE 4 is a perspective view of the completed tray.

Blanks 10 as illustrated in FIGURE 1 are formed by steel rule cutting dies and creasing dies which are well known to the art. There are score lines 11 parallel with the sides of the blank 10 which extend the length thereof and define the side panels 12 of the tray to be formed, and there are score lines 13 parallel with the ends of the blank and extend thereacross which define reinforcing

2

flaps 14. Parallel with the end score lines 13, and at a distance therefrom equal to the width of the side panels 12, there are transverse cuts 15 which extend into the side panels, where they curve, at 16, and then extend diagonally along straight lines 17 to the intersections of score lines 11 and 13. The last described transverse cuts 15 define the end panels 18 of the tray and the remaining connecting cuts define tabs 19 which are subsequently secured to the side walls 12. That area of the blank 10 within the intersecting score lines 11 and 13 becomes the bottom panel 20 of the tray.

The blanks 10 are fed into a conventional box making machine of proper size where the first step is to fold the end panels up and outwardly 180 degrees. At the same time the reinforcing flaps 14 are turned under the ends of the side panels 12 and by reason of the described widths of the flaps 14 and the end panels 18 there remains a transverse opening 21 near each end of the tray. Glue 22 is applied to the inner surfaces of the side panels at the ends thereof, but stitching (not shown) may be used instead after the tray has been completely folded.

The partially formed blank then passes into the forming head of the machine where the plunger presses the bottom panel 20 between forming plates. Part of this action is shown in FIGURE 3, and after the action is completed the tray is fully formed as shown in FIGURE 4.

The invention is not limited to the exemplary construction herein shown and described, but may be made in various ways within the scope of the appended claim.

What is claimed is:

1. In a tray made from a single rectangular blank of bendable sheet material, said blank being comprised of first score lines extending the full length thereof parallel with the blank sides and defining the width of side panels, transverse cuts in said blank parallel with the ends thereof and defining the upper edges of end panels, said transverse cuts extending into the defined side panels widths, second score lines extending the width of said blank parallel and with the ends thereof and intersecting said first score lines, diagonal cuts extending from the intersections of said score lines to the ends of said transverse cuts, the areas of said blank between said transverse cuts and said second score lines defining end panels and the areas of said blank between the ends thereof and said second score lines defining reinforcing flaps, the areas outwardly of the said first score lines at the ends of said end panels defining hinged tabs, the area between said first and second score lines defining a bottom panel, the construction wherein said side and end panels are perpendicular to said bottom panel along said first and second score lines, said reinforcing flaps are positioned beneath the lower surface of said bottom panel and extend upwardly over the outer areas of said side panels at the ends thereof and means attaching said tabs to said side panels.
